UNITED STATES PATENT OFFICE.

ARCHIBALD J. TURNER, OF CHICAGO, ILLINOIS, ASSIGNOR TO WILSON-WESTERN SPORTING GOODS CO., OF CHICAGO, ILLINOIS, A CORPORATION OF DELAWARE.

BASEBALL GLOVE.

Application filed September 7, 1926. Serial No. 133,824.

My invention relates to gloves such as are used in playing baseball, and in the following description and claims, I use the term glove as a generic term including all types of gloves or mitts, having one or more digit casings separate from other digit casings or from the rest of the hand.

Among the salient features of my invention are:

10 First. The provision of novel adjustable connecting means between the thumb and forefinger cover pockets of baseball gloves or mitts.

15 Second. The provision of said adjustable connecting means having no metal parts apt to injure a player or his clothing during playing,—as for instance in tagging a base runner.

20 Third. The provision of an adjustable connecting means comprising a substantial area of flat leather between the thumb and forefinger, thereby providing a substantial catching area between these digits.

25 Fourth. The provision of a connecting means having all the combined advantages of a flat leather web and an adjustable tension member.

Other objects of my invention will appear from the following description and the accompanying drawings, in which similar characters and references indicate similar parts throughout the several views.

In the drawings,

Fig. 1 is a view showing a fielder's glove provided with my improved connecting means, and

Fig. 2 is a detailed view of my connection between the thumb and forefinger.

The baseball glove shown in Fig. 1 comprises the usual pad or cushioning means (not shown), which is enclosed in a suitable leather case or covering. This covering comprises a plurality of sheets or pieces of leather, of which 10 indicates the outer palm covering, an integral piece of leather including portions for the front of each outer finger covering 11, 12, 13, and 14, and also the rear portions of the forefinger 14 and the little finger 11. The glove is provided with an inner lining of the usual type, having separate finger pockets for each finger and for the thumb, and the space between the respective outer and inner linings is filled with cushioning means disposed to protect the hand of the wearer, particularly

at the point of impact where the ball is caught. The lining and cushioning means of the thumb pocket is constructed in a manner well known to those skilled in the art, but in order to join the outer thumb casing 15 and the outer forefinger casing 14 to form a better catching surface, I provide improved connecting means 16 which may be made of any flat, flexible, wear-resisting material, but which I prefer to construct as follows:

The outer forefinger casing 14 is provided on its back side adjacent to thumb with a small piece or tab of leather 38, having the edge near the outline of the finger pocket turned in and sewed with the seam of the said finger pocket as at 17, and the other edges are also stitched firmly to said finger pocket as at 18. The leather piece 38 is provided with a plurality of holes 19, 20, 21, 75 and 22, and the flexible leather thong 24 is passed through these holes in any manner adapted to conveniently fix the same to the leather piece, with parallel thongs extending therefrom, but I prefer to fix the same as follows:

The thong 24 is passed in at the aperture 19 between the tab 38 and the finger casing, thence under the tab and out the aperture 20, thence over the surface of the tab 38 into aperture 21 and out aperture 22, the thong being drawn through said tab until its ends are approximately equal.

The outer thumb pocket 15 at its rear surface adjacent the forefinger is likewise provided with a small piece of leather 25, which is likewise stitched, or otherwise secured to the thumb casing, the best method of securing the same being to stitch in one edge of the said leather piece with the regular seam of the outer thumb casing as at 26, continuing the stitching around the other edges of the leather piece as at 27. The leather piece 25 is likewise provided with a plurality of holes 29, 30, 31, and 32 for securing the leather thong 24, the ends of which pass in at apertures 29 and 31, respectively, and out at apertures 30 and 32, respectively, and are tied by a knot 28, which may be of a permanent nature or a bow-knot, suiting the needs of the player.

The leather thong 24 is thus disposed with two substantially parallel tension members 23 and 24 extending between said thumb and forefinger pockets, and by my invention

- these tension members are covered with a flat tubular casing member, preferably of leather which presents the substantial area of a web of leather between these digits, yet 5 permits adjustment to suit the needs of each individual player, and constitutes a connecting means of great durability and which is cheap in manufacture and easy to assemble.
- 10 The tubular leather casing 16 is formed of a rectangular piece of leather, by simply folding over the two ends equally to meet in the center at 33, and stitching along each of the adjacent abutting edges as at 34 and 15 35 through both the said edges and the main portion of the rectangular piece of leather, thus forming a flat tubular leather member, having two tubular chambers 36 and 37, extending therethrough for the parts 20 of the thong 23 and 24 respectively.

Before attaching the ends of the thong to the thumb tab 25, these ends are passed through the chambers 36 and 37, after which the thong is fixed to tab 25 as described.

- 25 From the foregoing it will be obvious that my invention is not limited to use in joining thumb and forefinger of gloves alone, but may be used on mitts of all kinds and between other fingers when it is desired 30 to connect the same.

While I have illustrated and described the preferred formation of construction for carrying my invention into effect, this is capable of many modifications without departing from the spirit of the invention, and I do not wish to be limited to the precise details of the construction set forth, but desire to avail myself of all advantages 35 within the scope of the appended claims.

- 40 What I claim as new and desire to secure by Letters Patent of the United States is:

1. In a hand protecting covering having separate casings for certain digits, means for connecting said casings comprising spaced tension members fastened to said casings, and flat means supported by said tension members between the same.

2. In a hand protecting covering having separate casings for certain digits and means for connecting said casings comprising substantially parallel tension members fastened to said casings, said members being encased in a relatively flat leather casing.

3. In a hand protecting covering having separate casings for certain digits, means for connecting said casings comprising substantially parallel tension members fastened to said casings and a flat, tubular leather casing covering said members.

4. In a hand protecting covering having separate casings for certain digits and means for connecting said casings comprising adjustable leather tension members fastened to said casings and a flat, tubular leather casing covering said members.

5. In a hand protecting covering having separate casings for certain digits, means for connecting said casings comprising a plurality of tension members and means for connecting and covering said tension members and comprising a flat, tubular member of flexible material.

6. In a baseball glove, means for connecting the outer thumb and forefinger casings, comprising leather pieces having their peripheries sewed on the exterior of said casings, said pieces having a plurality of holes, a leather thong passing through a plurality of holes in each piece, and having its ends joined to form spaced tension members connecting said casings, and a flat leather piece folded and sewed to form a tubular leather casing about said tension members.

7. In a baseball glove, means for connecting the outer thumb and forefinger casings comprising leather pieces having a part of their peripheries turned in and stitched with said casings and the balance of the peripheries stitched to said casings, said pieces having a plurality of holes therein, a flat leather piece having its ends folded and stitched to said piece along medial lines forming a flat tubular member, a leather thong passing through a plurality of holes in the first of the first mentioned leather pieces, through said flat tubular member, thence through a plurality of holes in the second of the first mentioned pieces, thence through said tubular member, thence through a plurality of holes in said first of the first mentioned leather pieces, the ends of said thong being adjustably secured together.

8. In a baseball glove, means for connecting the outer thumb and forefinger casings, comprising leather pieces having their peripheries sewed on the exterior of said casings, said pieces having a plurality of holes, and tension members fixed to said casings by means of said holes.

9. In a baseball glove, means for connecting the outer thumb and forefinger casings, comprising leather pieces having their peripheries sewed on the exterior of said casings, said pieces having a plurality of holes, and substantially parallel tension members fixed to said casings by means of said holes.

10. In a baseball glove, means for connecting the outer thumb and forefinger casings, comprising leather pieces having their peripheries sewed on the exterior of said casings, said pieces having a plurality of holes, substantially parallel tension members fixed to said casings by means of said holes, and a flat tubular leather means connecting said tension members and extending over the area between them.

In witness whereof, I hereunto subscribe my name this 31st day of August, 1926.

ARCHIBALD J. TURNER.
